CLAIM

The ornamental design for a probe for prevention of post-partum hemorrhaging, as shown and described.

DESCRIPTION

FIG. 1 is a perspective view of a front surface of a probe for prevention of postpartum hemorrhaging showing our new design;

FIG. 2 is a front view thereof, the rear being a mirror image thereof;

FIG. 3 is a side view thereof, the opposite side being a mirror image thereof;

FIG. 4 is a top plan view thereof; and,

FIG. 5 is a bottom plan view thereof.

The portions of the figures illustrated in broken lines are provided for illustrative purposes only and form no part of the claimed design.
